WINCH CONTROL MECHANISM

Alfred W. Evans, Gloucester, Va.

Application April 30, 1947, Serial No. 744,882

2 Claims. (Cl. 74—397)

1

This invention relates to control mechanism for winches, and more particularly to such mechanisms for use with heavy duty winches of the type disclosed in U. S. Patent No. 2,361,388.

Patent No. 2,361,388 relates to heavy duty winches which include high and low speed drives, with the cable drum being bodily shiftable to secure selective engagement with said high and low speed drives. In this patent, a lever is employed to accomplish the shifting of the cable drum, the lever being connected to the end of the cable drum shaft. It was found that this manner of shifting the drum was not suitable when the winch was installed upon extremely heavy equipment, such as motor cranes, etc. For such installations, a smoother operating mechanism which can be remotely controlled, is desirable.

The object of the present invention is to provide such control mechanism, wherein the control may be either automatic and remotely positioned, or manual and controlled at the winch.

Another object of the invention is to provide winch shifting means containing power multiplication for ease in shifting under heavy load, the parts being arranged to obtain a high degree of smoothness and efficiency in operation.

Other objects of the invention will be apparent from the following description of a preferred and practical embodiment of the invention, when taken in conjunction with the drawings which accompany, and form a part of, this specification.

In the drawings:

Figure 1 is a side view of a power winch of the type shown in the above mentioned patent, with the device of the present invention applied thereto;

Figure 2 is a view of the opposite side of the winch;

Figure 3 is a vertical section through the winch with the present invention applied to the cable drum shaft;

Figure 4 is a somewhat diagrammatic section taken on the line 4—4 of Figure 3;

Figure 5 is a vertical section taken on the line 5—5 of Figure 1;

Figure 6 is a section through the control valve taken on the line 6—6 of Figure 1; and

Figures 7 and 8 are sections taken on the lines 7—7 and 8—8, respectively, of Figure 6.

Referring to the drawings in detail, there has been shown enough of the winch disclosed in Patent No. 2,361,388 to illustrate the operative relation of the present invention to the winch, and the results to be obtained thereby.

Briefly, the winch comprises a pair of spaced

side plates 1 and 2, having mounted between them a flanged cable drum 3. Bolted to one flange of the drum is a ring gear 4 having external teeth 5, to mesh with spaced gears 6 and 7 constituting the low speed drive, and internal teeth 8, to mesh with a high speed gear 9. Gears 6 and 7 are mounted on shafts 10 and 11, which carry on their respective outer ends gears 12 and 13 meshing with a drive gear 14. The gear 14 is carried on a shaft 15, and receives power from a suitable source through a sprocket 16 and chain 17, the sprocket 16 being mounted on the shaft 15. High speed gear 9 is mounted upon a shaft 18 which carries on its outer end a gear 19 positioned to be constantly in mesh with the gear 13, and, through the gear 13, receives its power from the drive shaft 15.

Cable drum 3 is mounted upon a central shaft 20 which is housed in bearings carried by the side plates 1 and 2. Eccentric disks 21 and 22 are mounted upon the ends of the shaft 20 and are journaled in bearings 23 and 24 carried by the side plates. As clearly shown in Figures 1, 2 and 3, the shaft 20 is eccentrically mounted in the disks 21 and 22, and the disks are concentrically positioned for rotative movement within the bearings 23 and 24. Rotation of the disks will cause the shaft and drum to move along an arcuate path so that the drum may be lifted to engage the external teeth 5 of the ring gear with the low speed gears 6 and 7, or, the drum may be dropped to engage the internal teeth 8 of the ring gear with the high speed drive gear 9. All of the above is set out quite clearly and in detail in the above mentioned patent.

The present invention concerns means for causing rotative movement of the eccentric disks 21 and 22 and comprises mounting a segmental gear 25, having a toothed area 26, upon one of the eccentric disks. It is preferable to mount it upon the disk 21 so as to be on the opposite side of the machine from the driving gears. The gear 25 is mounted concentric to the disk 21, and, in order to space the gear 25 from the side plate, a spacer disk 27 is interposed between the segmental gear 25 and the disk 21. It is preferred to employ a cover plate 28 in front of the segmental gear, the cover plate 28 being of greater diameter than the gear so as to extend beyond the gear around its entire periphery. The segmental gear 25, spacer 27 and cover plate 28 are all held to the eccentric disk 21 by means of bolts 29.

At a point spaced from the above described assembly, a bell crank lever 30 is pivotally

mounted upon the side plate 1. This bell crank comprises an operating arm 31 and an arm 32 having an arcuate outer edge provided with gear teeth 33, the gear teeth 33 being adapted to mesh with the teeth 26 of the segmental gear 25. A spacing block 34 is positioned between the bell crank 30 and the side plate to place the lever 30 in the same vertical plane with the segmental gear 25. It will be obvious that a rocking movement of the lever 30 will cause rotative movement of the eccentric disk 21 and thereby cause the cable drum 3 to be raised into low speed position or lowered into high speed position. The cover plate 23 forms, in effect, an annular flange beyond the teeth of segmental gear 25, and will hold the gear sector against movement to prevent disengagement of the gear sector and segmental gear.

Extending outward from the side plate 1 are ears 35 and 36, carrying adjustable stops 37 and 38. These stops are arranged in the plane of the arm 31 of lever 30, as is clearly shown in Figure 5, to limit the movement of the arm in its forward and rearward travel. As the driving gears of the winch become worn, the stops 37 and 38 can be adjusted to increase the travel of the arm 31 and thereby increase the movement of the cable drum 3 to insure positive and tight engagement of the teeth of the ring gear with the high and low speed drives.

When installed upon heavy equipment the winch usually will be placed either at the front or the rear of the machine, and sometimes in both places, and should be under the direct control of the operator who is usually seated in a cab, often at some distance from the position of the winch. Both manual and automatic means are provided for operating the lever 30. The lever 30 may be rocked manually, by an operator standing near the winch, by means of a handle 39 which is bolted to the bell crank 30. The automatic control comprises a pneumatic cylinder 40 having a link 41 connected to its piston shaft 42, the link having its opposite end connected to the arm 31 of the bell crank 30. Reciprocatory movement of the piston will cause oscillation of the bell crank. Cylinder 40 is a double acting one and has air lines 43 and 44 connected to its opposite ends, the air lines passing through a control valve 45 preferably located in the cab of the machine. The pipe 46 is also connected to the control valve and leads from an air reservoir 47. The air reservoir is kept under constant pressure from a source of air through a supply line 48 and feed valve 49. The valve 45 may be of any conventional type which, when turned to one position, will connect pipe 43 with the reservoir and will bleed the pipe 45 to atmosphere. This will cause the piston and cylinder 40 to move to the left as viewed in Figure 1, rocking the bell crank in a counter-clockwise direction and thereby causing clockwise rotation of the eccentric disk 21 and movement of the drum 3 to cause engagement of the ring gear with the high speed drive. Movement of the valve 45 to another position will connect the pipe 44 with the reservoir 47 and bleed the pipe 43, causing a reverse movement of all of the parts.

As mentioned above, any conventional type valve having the necessary ports will suffice for valve 45. However, a typical valve is illustrated in Figures 6, 7 and 8 of the drawings. This valve comprises a housing 50, having a central circular bore to receive a valve body 51, held in rotatable position within the housing by means of an

upper flange 52 and a washer 53 which is fastened to the body by a bolt 54. An operating handle 55 is provided to turn the body within the housing. Pipes 43, 44 and 46 communicate with openings 56, 57 and 58, respectively, the openings 56 and 58 being opposite one another, and the opening 57 being at right angles to the axis of openings 56 and 58 and the openings being in a common plane. The housing is provided with a fourth opening 59, which is oppositely positioned with respect to opening 57 but on a different plane from the openings 56, 57 and 58. The valve body is provided with two T-shaped ports 60 and 61, one of the ports being turned 90 degrees with respect to the other. The port 60 is positioned within the body to lie in the same plane as the openings 56, 57 and 58 of the housing, and the port 61 to lie in the plane of opening 59. Port 61 has an offset 62 leading upward to the plane of port 60. With the valve body turned to the position shown in Figures 6, 7 and 8, port 60 will connect pipes 43 and 46 so that air will flow into the right-hand end of cylinder 40 (as viewed in Figure 1), to move the winch into low gear. At the same time, port 61 and its extension 62 will connect pipe 46 with opening 59 to exhaust the left-hand side of cylinder 40 to atmosphere. When handle 55 is turned 90 degrees in a counter-clockwise direction, port 60 will connect pipes 44 and 46 to move the piston in the opposite direction, and extension 62 and port 61 will connect pipe 43 to atmosphere.

It will be noted that the valve may be left in either of its operative positions, thereby maintaining a constant pressure upon the cylinder to hold the lever arm 31 tightly in engagement with the respective stops 37 and 38, and any leakage of air past the cylinders will be compensated for by additional air from the reservoir. With this arrangement there can be no possibility of the winch slipping out of gear. By bringing the valve body 51 to a position intermediate those described above, after the arm 31 has reached a point between the stops 37 and 38, all openings of ports 60 and 61 will be out of communication with the openings of the housing and the piston within the cylinder 40 will be held against further movement in either direction, and the winch will be held in a neutral position.

It will be obvious from the above that this structure will give the operator complete control over the winch at all times, and that the harmonic motion employed in turning the cable drum shaft will insure ease and smoothness of operation.

Although in the above there has been described one practical embodiment of the invention, it is to be understood that changes may be made from the precise structure shown without departing from the scope of the appended claims.

Having thus fully described the invention, I claim:

1. In a winch gear shifting mechanism means to control the movement of an eccentrically mounted shaft comprising, a segmental gear concentric with and carried by the eccentric mounting of said shaft, a bell crank pivoted at a point remote from said shaft mounting and having one arm forming a gear sector to mesh with said segmental gear, fluid means to rock said bell crank, a cover plate of larger diameter than said segmental gear mounted concentrically to said gear to prevent lateral movement of said gear sector and disengagement of said segmental gear and gear sector, and adjustable stops positioned in

the path of movement of said bell crank to limit its rocking movement in both directions.

2. In a winch gear shifting mechanism means to control the movement of an eccentrically mounted shaft comprising, a segmental gear concentric with and carried by the eccentric mounting of said shaft, a bell crank pivoted at a point remote from said shaft mounting and having one arm forming a gear sector to mesh with said segmental gear, a cover plate of larger diameter than said segmental gear mounted concentrically to said gear to prevent lateral movement of said gear sector and disengagement of said segmental gear and gear sector, adjustable stops positioned in the path of movement of said bell crank to limit its rocking movement in both directions, a cylinder and piston, said piston being connected to said gear sector, a source of air supply, air lines from said source of supply connected to both ends of said cylinder, and a valve having port openings which may be positioned to; admit air to one end of the cylinder and exhaust

air from the other end, admit air to the second end and exhaust air from the first end, cut off air admission and exhaust from both ends of said cylinder.
